UNITED STATES PATENT OFFICE

BENJAMIN L. FRY, OF ST. LOUIS, MISSOURI, ASSIGNOR TO NATIONAL SALES MACHINE COMPANY, OF ST. LOUIS, MISSOURI, A CORPORATION OF MISSOURI

COIN RECEPTACLE FOR VENDING MACHINES

Application filed November 18, 1929, Serial No. 408,081. Renewed March 7, 1932.

This invention has for its object the provision of means whereby coins and slugs inserted in the coin slot of a vending machine will be separately collected. The invention is 5 illustrated in the accompanying drawings and will be hereinafter fully set forth and defined.

In the drawings:

Figure 1 is a perspective view of a vending 10 machine having the invention embodied therein,

Fig. 2 is a vertical section from front to rear through the lower portion of the machine, and

Fig. 3 is a detail section on the line 3—3 of Fig. 2.

The drawings show a cabinet having a base portion 1 which is closed at its front side by doors 2 hinged at the ends of the cabinet and 20 arranged to meet a jamb 3 at the center of the front, the doors being provided with suitable locks the key to which will be in the possession of the owner of the machine. The upper portion of the cabinet provides a plurality of columns each containing a series of compartments 5 in each of which is placed one article or package which is offered for sale. Vertically movable closures 15 cover the fronts of the several columns and panels 30 16 cover the edges of the closures and impart a neat finish to the cabinet.

The several closures are shifted to open position, exposing the respective compartments, by mechanism which is actuated by a 35 selected plunger 34 after a proper coin is inserted, the mechanism being inoperative until the coin is inserted.

Upon referring to Figs. 1 and 2, it will be noted that the base portion of the cabinet is 40 considerably greater in depth than the upper portion containing the selling columns, thereby producing a shelf-like structure in which are coin slots 54 alined with the respective columns whereby an intending purchaser 45 may deposit the coin in the proper slot to effect operation of such closure as will uncover the desired merchandise.

Alined with the respective columns and corresponding coin slots are display pockets 55 which are arranged in the top of the cabi-

net base between the coin slots and the columns, as shown in Fig. 2, the several pockets being covered by a panel 56 of glass or other transparent material. The pockets have a common bottom 57 which is hinged at its rear edge to the under side of the top 58 and is held in closed position to support the samples, indicated at 59, by latches of any approved type. It will be understood that in each pocket is placed a sample of the articles which are offered for sale in that column in advance of which the pocket is located and, of course, the prospective customer will deposit his coin in the slot immediately in front of the selected sample. The several plungers 34 are arranged below the respective coin slots, as indicated in Fig. 1, and each plunger is equipped with a knob or other handle 60 to facilitate its operation. A coin chute 61 mounted in the cabinet extends upwardly to a point immediately below the corresponding slot 54 so that the inserted coin will be directed to a coin rest so located that the coin thereon will cooperate with the plunger to effect the desired operation of the closure. This coin chute is equipped with mechanism whereby slugs or other spurious devices are rejected and turned aside so that they will not pass to the coin rest, the particular structure of these slug-rejecting devices being immaterial in the present invention.

Within the base of the cabinet, there is provided a hopper 62 which is constructed with a central vertical partition 63 and which at its upper end extends the full width of the cabinet so as to be disposed under all the coin chutes and adapted to receive coins therefrom. The central partition 63 divides the hopper into two compartments 64 and 65, the front compartment 64 receiving the coins and directing them into the coin box 66 which is placed upon the floor of the cabinet, as clearly shown, while the compartment 65 receives the slugs and directs them into the rear box 67. The boxes 66 and 67 are preferably one integral structure and are placed upon the floor of the cabinet immediately at the rear of the jamb 3 and bearing against the jamb or a stop block at the inner side of the jamb. The rear end of the box bears against a brace 68.

- secured upon the floor of the cabinet and extending from side to side of the same, as shown. The lower end of the hopper is supported by a bracing bracket 69 and a cleat or stop bar 70 is secured upon the floor of the cabinet adjacent the foot of said bracket. One side of the box is disposed against the cleat or stop 70 and a latch 71 is hingedly mounted upon the floor of the cabinet at the opposite side of the box and adapted to abut the same so that the box will be very firmly held in place by and between the jamb 3 at the front and the brace 68 at the back and between the stop 70 and the latch bar 71. When the box is to be removed, the latch bar 71 is easily swung upwardly to permit the box to be moved laterally so as to clear the jamb and then brought forwardly through the doorway of the cabinet.
- It will be noted that the upper end of the hopper 62 extends the entire width of the cabinet while the side and end walls thereof converge or taper downwardly in the direction of the coin receiving box so that the coins or slugs are separated and positively directed into their respective compartments formed by the central partition 71 of said coin box.

In operation, when the knob 60 is actuated to vend a commodity, the good coins will drop from the coin mechanism into the front compartment and be directed downwardly into the compartment 66. Should an attempt be made to fraudulently operate the machine by the insertion of a slug or spurious coin, the latter will be ejected and directed downwardly into the rear compartment 65 by the chute 73, indicated in dotted lines in Fig. 2 of the drawings. By unlocking the doors of the cabinet and elevating the latch 71, the coin box may be readily removed and the separated good and spurious coins conveniently emptied therefrom and the coin box replaced. It will thus be seen that there has been provided a comparatively simple and thoroughly efficient means whereby both good and spurious coins may be collected and deposited in a suitable retainer so that they may be conveniently removed at one time from the machine.

Having thus described the invention, I claim:

In a vending machine cabinet having a plurality of coin-controlled mechanisms therein extending in a series from side to side thereof, a hopper disposed below said mechanisms and having its upper end coextensive with the series and its sides converging downwardly, a partition disposed within the hopper and forming front and rear compartments, and a coin receptacle disposed beneath the small end of the hopper and provided with a central partition defining separate compartments registering with the compartments of the hopper.

In testimony whereof I affix my signature.

BENJAMIN L. FRY.
